UNITED STATES PATENT OFFICE.

PAUL I. ANDREWS, OF KENNEBUNK, MAINE.

REINFORCED WAREHOUSE CAR AND BOX.

1,057,913.

Specification of Letters Patent.

Patented Apr. 1, 1913.

Application filed March 27, 1912. Serial No. 686,681.

To all whom it may concern:

Be it known that I, PAUL I. ANDREWS, citizen of the United States, residing at Kennebunk, county of York, State of Maine, have invented a certain new and useful Improvement in Reinforced Warehouse Cars and Boxes, of which the following is a specification, reference being had therein to the accompanying drawings.

10 Sheets of leatheroid, so-called, and fiber board are extensively used in the manufacture of warehouse and factory push cars and boxes which are employed for trans-
ferring goods from one place to another
15 about the building. In order to withstand the hard uses to which the cars are put it is necessary to reinforce the edges and corners of the car.

The present invention relates to the means
20 for reinforcing the edges and corners of cars made of leatheroid or other sheet material.

The invention will be fully understood
25 from the following description taken in connection with the accompanying drawings, and the novel features will be pointed out and clearly defined in the claim at the close of the specification.

In the drawings—

30 Figure 1 is a perspective view of a car embodying the invention. Fig. 2 is a perspective view showing one of the bottom corners of the car having attached thereto a reinforce embodying the invention. Fig. 3 is a vertical section through the bottom and corner reinforce, shown in Fig. 2.

Referring now to the drawings:—the sides and ends 1 of the box may be made of any suitable material, as for instance, leatheroid, the bottom 2 of the box usually being made of wood. The corners of the box where the joint is formed between one end and one side is reinforced on the outside by a corner piece 3 which is shaped to fit 45 over the corner and lap onto the ends and sides and extends nearly to the top of the box. These reinforcing corner angle pieces may be secured by rivets 4 or in any other suitable way.

50 To protect the bottom of the box at the edges an angle plate of metal is provided having a flat portion 20 which extends beneath the lower edge of the side or end wall

1 of the car and also laps over onto the bottom 2 of the car. The upright portion 55 of the angle plate has a flat portion 21 which contacts with the wall 1 of the car and through which nails or other suitable fastening means 22 are driven into the bottom 2 of the car to secure the angle plate in position. 60 Where the angle plate turns the corner of the bottom it is preferably formed with a corrugation 23 and also there is another corrugation 24 above the flat portion 21, the two corrugations 23 and 24 serving to 65 strengthen the angle plate and to better protect the car. As there will be a gap between the adjacent ends of two of the angle plates at the corner of the box, a corner reinforce is also provided which laps onto the bottom 70 as well as around the corners of the car, as shown in Fig. 2. This corner piece is provided with concave portions 25, 26, which fit onto the convex corrugations 23 and 24 of the bottom binders and has flat inset 75 portions 27 which fit into the inset portions 21 of the bottom angle plates.

What I claim is;

A metallic bottom binder for a box consisting of a metallic angle plate bent in such 80 manner as to have a flange which extends from the bottom of the side wall upwardly and a flange which extends beneath the lower edge of the side wall and laps onto the under side of the bottom of the box, 85 said side flange being formed with a corrugation where it turns the corner and another corrugation at some distance above the first corrugation and a flat intermediate portion which lies flat against the wall of 90 the box, in combination with a metallic corner reinforce consisting of an angle plate formed with flanges which extend beneath the bottom of the box and flanges which extend up against two adjacent sides of the 95 box and wing portions having top and bottom corrugations and intermediate portions which fit outside of the corrugations and intermediate flat portions of the two adjacent bottom binders.

In testimony whereof I affix my signature, in presence of two witnesses.

PAUL I. ANDREWS.
